**HANDLE FOR UNDERWATER VEHICLE FOR
PULLING DIVER THROUGH THE WATER
OR THE LIKE**

George J. Peroni, Miami, Fla., assignor to Seatech
Corporation, Miami, Fla.

Filed Feb. 16, 1972, Ser. No. 227,008

Term of patent 14 years

Int. Cl. D12—16
U.S. Cl. D12—70

FIG. 1

FIG. 2

FIG. 3

FIG. 4

FIG. 5

FIG. 6

FIG. 7

FIG. 1 is a perspective view of the handle for underwater vehicle showing my new design;

FIG. 2 is a side view of the handle for underwater vehicle shown in FIG. 1 illustrating in plan view the receiving surface for the palm of the hand of the user and the rearwardly directed supporting skirt;

FIG. 3 is a side view of the handle for underwater vehicle opposite to the side shown in FIG. 2;

FIG. 4 is a front view of the handle for underwater vehicle shown in FIG. 1 illustrating in plan view the ridges for separating the fingers of the hand of the user;

FIG. 5 is a rear view of the handle for underwater vehicle shown in FIG. 1;

FIG. 6 is a top view of the handle for underwater vehicle shown in FIG. 1; and

FIG. 7 is a bottom view of the same.

I claim:

The ornamental design for a handle for underwater vehicle for pulling diver through the water or the like, as shown.
